UNITED STATES PATENT OFFICE.

HENRY C. NICHOLSON, OF MOUNT WASHINGTON, OHIO.

ELECTRIC RAILWAY-SIGNAL.

SPECIFICATION forming part of Letters Patent No. 275,255, dated April 3, 1883.

Application filed January 31, 1883. (No model.)

To all whom it may concern:

Be it known that I, HENRY C. NICHOLSON, a citizen of the United States, residing at Mount Washington, in the county of Hamilton and State of Ohio, have invented certain new and useful Improvements in Electric Railway-Signals; and I do hereby declare the following to be a full, clear, and exact description of the invention, such as will enable others skilled in the art to which it appertains to make and use the same.

This invention relates to that class of electrical signals disposed in so-called "blocks" along a railroad, in which the signaling-circuits are brought into action, either directly or indirectly, by the trucks of a passing locomotive or train, rails of the track constituting a part of the circuits, main or secondary, as the case may be.

One object of my invention is to so organize the circuits that the signals at both ends of a block may be synchronously operated by a make and break in the electrical connections effected by a locomotive or train on entering a block and again on passing out of it, so that but a short section of the track requires to be insulated at each signal-station.

Another object of my invention is to so organize the circuits and signals that each block may contain one or more signals intermediate between the signals at its ends, and that all the signals in the block will be operated synchronously each time a locomotive or train passes any one of the signal-stations thereof, so that the position of such locomotive or train at any one station or between any two stations of such block will be indicated at all the stations thereof.

Another object of my invention is to so combine the rails of the track with the other permanent electrical conductors that a hand-car may pass along the track without operating the signals.

With these objects in view my invention consists of certain combinations of electric signaling-circuits with the rails of a railroad-track; also, of a step-by-step signal, all as specifically pointed out in the claims at the close of this specification.

In order that my invention may be clearly understood, I have illustrated in the annexed drawings, and will proceed to describe some

practical forms of signaling-circuits embodying it, and also one form of a step-by-step signal which may be used in connection therewith.

Figure 1 is a diagram of a simple form of my invention. Fig. 2 is a similar diagram, but differing from Fig. 1, in that it shows a provision for allowing the passage of hand-cars without effect on the signals. Fig. 3 is a diagram of the preferred form of my invention as embodied in a block with a signal at each end only. Fig. 4 is a diagram of one form of my invention as embodied in a block containing signal-stations intermediate between the two end stations. Fig. 5 is a sectional front elevation of the step-by-step signal. Fig. 6 is a plan view of said signal. Fig. 7 illustrates means for holding the door of the signal-case locked until the motor has been wound up.

The same letters of reference indicate identical parts in all the figures.

In all the diagrams, A refers to the rails of one side, and A' to the rails of the other side, of the track of a railway.

In Fig. 1 the signal-block consists of an electric circuit containing a signal at each end, the signals being marked B and B', respectively, and organized to operate with a step-by-step movement in such manner that one establishment and withdrawal of an electric current will effect the display of either the danger-disks or the safety-disks, as the case may be. One form of such signal will be hereinafter described, but other forms may be used. The line-wire 1 of the signaling-circuit is stretched from the positive pole of a battery, M B, at one end of the block to the positive pole of a battery, M B', of equal strength, at the other end, the negative pole of each battery being connected to earth. Near one end, and preferably at a point between the battery M B and the signal B, the line is connected by a wire, 2, to an insulated section, a, of the rails A of the track. At the other end the line is similarly connected by a wire, 3, to an insulated section, a', of the rails A of the track. The rails A' are, at points opposite the respective insulated rail-sections, connected to earth by wires 4 and 5. The insulated rail-sections are of such length that they cannot be bridged by any two adjacent trucks of a locomotive or train, so that when a connection has once been made be-

tween the wires 2 and 4 or 3 and 5 by the first truck of a passing locomotive or train such connection will not be broken until the last truck thereof passes from the insulated rail-section. Should there be a joint in the insulated rail-sections or in the rails opposite, I prefer to connect the adjacent ends of the rails at the joint by a permanent conductor—such as a short wire soldered to the respective rails—in addition to the ordinary fish-plates, in order to insure the metallic continuity at such joints.

Let it be supposed that there is no locomotive or train either between or at the signal-stations of the block. In that—the normal—condition the batteries M B and M B' *nil* each other, so that no current manifests itself on the line and the signals display their safety-disks. If, now, a locomotive or train enters upon either insulated rail-section, the line will be connected to earth, so that currents will flow from the respective batteries over the line in opposite directions to the wire 2 or 3, as the case may be, and thence to earth through the trucks of the locomotive or train. Both signals will be operated synchronously so as to advance and display one-half of the surface of the danger-disks. As the locomotive or train continues advancing it passes from the insulated rail-section at the end where it entered the block. The line is thus again disconnected from the earth and the flow of the currents is again interrupted, which causes a further movement of the signals, and to such extent that now the whole surface of the danger-disks is displayed. On reaching the insulated rail-section at the farther end of the block the line is again connected to earth by the trucks of the locomotive or train and the signals are operated so as to withdraw one-half of the surface of the danger-disks and display one-half of the safety-disks; and, on finally passing out of the block the signals are again operated so as to wholly withdraw the danger-disks and display the safety-disks in full. It will be observed that with this organization of circuits and signals the latter not only indicate the presence of a locomotive or train in the block, but also whether it is at either of the signal-stations or between them.

The electric signal-block shown in Fig. 2 differs from that shown in Fig. 1 only in that opposite to the insulated rail-sections *a* and *a'* there are two earth-wires, 4 and 4^a and 5 and 5^a, respectively, and intermediate insulated rail-sections, *a*² and *a*³, of sufficient length to prevent the trucks of a hand-car from making a connection from the insulated rail-sections *a* or *a'* to the grounded rails at either end of the opposite insulated rail-sections, *a*² or *a*³. In this case the metallic parts between the trucks of locomotives or trains are depended on to make part of a metallic connection from the wire 2 to earth-wires 4 or 4^a or from the wire 3 to the earth-wires 5 or 5^a.

The electric signal-block shown in Fig. 3

differs from that shown in Fig. 1 in that the line is connected to earth by the action of local electro-magnets marked C and C', respectively, and operated by local batteries respectively marked L B and L B', the circuits of which are normally open, and are adapted to be closed only by the trucks of a locomotive or train, but not by the trucks of a hand-car. To these ends the insulated rail-sections are made only long enough to prevent the trucks of a hand-car from bridging them, while the trucks of a locomotive or train are able to bridge them so as to connect the wire 6 of the local battery with the wire 7 thereof through the locomotive or train trucks and the opposite rails A'. The wire 2 is connected to the front contact-point of local electro-magnet C, and the earth-wire 4 to the armature-lever of said magnet. The wires 3 and 5 are similarly connected to the front contact-point and armature-lever of the electro-magnet C'. The operation of the signals is precisely the same as in the block shown in Figs. 1 and 2. I prefer the use of locals for connecting the line to earth, because they are not so easily affected by slight disturbances as the electro-magnets of the line, so that in consequence of their use the operation of the signals is made more certain and correct. It is advisable to insulate one or more rails A next to the insulated rail-sections *a* and *a'*, so that the wires 6 and 7 cannot be connected except by the trucks of locomotives or trains.

Fig. 4 illustrates an electric signal-block in which there are two signals, D' and D², intermediate between the signals D and D³ at the ends of the block, and in which the line is connected to earth each time a locomotive or train passes any one of the signal-stations in the block by means of a local electro-magnet, the same as in the arrangement shown in Fig. 3. All the local circuits are connected to the rails, as shown in Fig. 3, except the local circuit at the left-hand end of the block, the wire 6 of which is connected to an insulated rail of one side of the track and the wire 7 to an insulated rail on the other side of the track, the adjacent ends of the respective insulated rails being separated so far that a hand-car cannot make a connection from one to the other. In the case of this local, the metallic parts between the trucks of a locomotive or train are in part depended upon for connecting wires 6 and 7. The construction of the signals applicable to an electric signal-block having signal-stations (one or more) intermediate between the signals at the ends of the block differs from that of the signals adapted to blocks containing but two signals, in requiring as many danger-disks as there are signals in the block. One form of such signal is illustrated in Figs. 5 and 6. It consists of a case, E, the front side of which is provided with four circular openings, e, e', e², and e³, arranged in an arc at the upper end of the box. The center of the arc of openings is coincident with the axis of a wheel, F, which is keyed to a horizontal shaft, G, and is ar-

ranged directly behind the front side of the case, so that its rim will cover the openings therein. The ground color of the face of the rim of wheel F is white; but along a portion of the rim four danger-disks are painted of such size and so spaced that on starting the wheel from its normal position by the step-by-step motor, presently to be described, the first step will throw the first danger-disk so far as to cover the first opening—saye—from one edge to the center, the second step so far as to cover the whole opening e, the third step so far the first danger-disk will cover the opening e' from one edge to the center and the second danger-disk the opening e also from one edge to its center, the fourth step so far that the first danger-disk will cover the whole opening e' and the second danger-disk the whole opening e, and so on until by the last step all the openings in the front of case E are first covered by the respective danger-disks on wheel F, which continues to turn, however, and so far as to immediately again withdraw all the danger-disks from behind the openings in the front of the case and cover them by the white surface on the rim of the wheel, indicating that the locomotive or train has passed out of the block, or "safety." The wheel F is operated by a clock-work like motor, the action of which is controlled by an electro-magnet, H, the helix of which constitutes part of the main line 1 of the signal-block. The armature of this electro-magnet is secured to a slide-bar, I, provided with suitable stops to limit its movements, and combined with a retractile spring, which acts antagonistically to the magnet. The slide-bar is also provided with two fixed arms or pallets, i and i', which are, by the actions of the magnet and the retractile spring on the slide-bar, brought alternately into position to stop the rotation of an arm, k, fast on shaft K of the motor, at every half-turn of said shaft. A pinion, K', on the shaft K is adapted to mesh into a segment of teeth of wheel G' on shaft G. In the present example, where there are four danger-disks, it requires eight steps to display all of them in full, and also return them to their normal positions, as before explained; hence the pinion K' is so proportioned to the segment of teeth of wheel G' that eight half-turns of the pinion will turn the wheel so far that at the termination of the last half-turn the last tooth of the segment of teeth of the wheel will escape from the pinion, thus allowing the wheel to continue rotating until stopped by the first tooth of the segment again engaging the pinion. It will be observed that the pinion K' and arm k serve only as a means for compelling the motor to turn the wheel F step by step. On account of this mode of operation I call this signal a "step-by-step" signal. When there is no current manifest on the line, and the armature of relay H consequently drawn back, the pallet i is in position to stop the rotation of arm k. The attraction of the armature moves the pallet i from under the arm k, which is then immediately put in

motion by the motor. If the magnet remains charged longer than it takes the arm k to make a half-turn it will be stopped by pallet i', to be released as soon as the armature is retracted, when the arm completes its rotation and is again stopped by pallet i. A locomotive or train may, however, pass a signal-station so rapidly that the armature is retracted before the arm k reaches pallet i', in which case it will make a full rotation without stoppage, the only difference in the operation of the signal being that the wheel F is moved a distance at one continuons impulse of the motor, which usually requires two separate impulses, each equal to half the duration of said continuous impulse. In either case it requires a make and break in the electric circuits to effect one entire rotation of arm k. The danger-disks may vary in color, so that by the color or colors displayed the position of the locomotive or train moving in a known direction will be indicated as being at or passing a signal-station, or as being between any two signal-stations. At night the wheel F will be illuminated by a lamp, L, arranged in case E.

In order to compel the attendant to wind the motor daily, I provide a contrivance which holds the door giving access to the lamp locked until the motor has been wound. In this case, where the motor is operated by a weight, this may be effected by a latch-lever, M, the heavy end of which projects over the weight near the winding-shaft, while its lighter end is constructed with a hook adapted to engage a keeper on the inside of the door.

To unlatch the door the motor must be wound until the weight lifts the heavy end of the latch-lever, as will be readily understood. The winding-shaft projects through the case, so that the key may be applied from the outside.

In order that the operator or station-keeper may be audibly notified of the shifting of the signals, I provide an electric alarm, N, which is rung each time the signals are shifted. The alarm is placed in a local circuit having two branches, in the manner shown, the pallet i being one terminal of one of the branches, the pallet i' one terminal of the other branch, and the arm k the other terminal common to both branches. The alarm rings when the circuit is opened. The pallets are insulated from the slide-bar.

When a signal of this character is applied to an electric signal-block containing only two signals—one at each end—the case E will have but a single opening in front of wheel F, and the latter will be provided with a continuous series of suitably-spaced danger-disks, and the wheel G' will have teeth all around its periphery.

The motor of the signal, whatever the latter's construction, may be stopped and started by a local electro-magnet, the circuit of which is opened and closed by the operation of electro-magnet H of the main line.

Having thus described my invention, what I claim is—

1. The combination, substantially as before set forth, of the closed main-line circuit, a battery at one end thereof, an equal but opposed battery at the other end thereof, and a normally-open connection from the main line to earth at each signal-station, adapted to be closed automatically by a locomotive or train.
2. The combination, substantially as before set forth, of the closed main-line circuit, a battery at one end thereof, an equal but opposed battery at the other end thereof, a normally-open connection from the main line to earth at each signal-station, and an independent local circuit at each signal-station containing an electro-magnet for closing and opening said connection in consequence of a make and break of such local circuit effected by a passing locomotive or train.
3. The combination, substantially as before set forth, of the closed main-line circuit, a battery at one end thereof, an equal but opposed battery at the other end thereof, a normally-open connection from the main line to earth at each signal-station, and a step-by-step signal at each signal-station.
4. The combination, substantially as before set forth, of the closed main-line circuit, a battery at one end thereof, an equal but opposed battery at the other end thereof, one or more step-by-step signals intermediate between the 30 step-by-step signals at the ends of the circuit, and a normally-open connection from the main line to earth at each signal-station.
5. The combination, substantially as before set forth, of the closed main-line circuit, a battery at one end thereof, an equal but opposed battery at the other end thereof, a normally-open connection from the main line to earth at each signal-station, and an insulated rail-section disposed, substantially as described, so 40 that a hand-car cannot effect the closure of said connection.

In testimony whereof I affix my signature in presence of two witnesses.

HENRY C. NICHOLSON.
